UNITED STATES PATENT OFFICE.

IRWIN HUEBNER, OF ALLENtown, PENNSYLVANIA.

DESIGN FOR AN AUTOMOBILE RADIATOR CAP.

Application filed January 11, 1928. Serial No. 24,809. Term of patent 14 years.

To all whom it may concern:

Be it known that I, IRWIN HUEBNER, a citizen of the United States, residing at Allentown, in the county of Lehigh and State of Pennsylvania, have invented a new, original, and ornamental Design for an Automobile Radiator Cap, of which the following is a specification, reference being had to the accompanying drawings, forming part thereof.

In the drawings Fig. I is a front elevation of an automobile radiator cap showing my new design; and Fig. II is a side view of the same.

I claim:

The ornamental design for an automobile radiator cap, as shown.

IRWIN HUEBNER.
